GEORGE H. DAVIS, OF BOSTON, MASSACHUSETTS.

Design No. 3,856, dated February 22, 1870.

DESIGN FOR A PIANO-CASE.

The Schedule referred to in these Letters Patent and making part of the same.

I, GEORGE H. DAVIS, of Boston, in the county of Suffolk, and State of Massachusetts, have invented a new and original Design for the Corners of a Piano-Forte Case, of which the following, with the accompanying drawings, is a description.

In the drawings—

Figure 1 represents a piano-forte case having all of its corners truncated by a vertical plane, and each diagonal face thus produced ornamented with a console or ornamental tablet.

Figure 2 represents a diagonal elevation of the case, showing a front elevation of one corner and its ornament, and a side elevation of two other corners and ornaments.

Figure 3 is a front elevation of the console or tablet, drawn to a larger scale.

Figure 4 is a side elevation of the same, and

Figure 5 is a horizontal section on the line x of figs. 4 and 5.

My new design consists, in the first place, in forming the corners of the case by small vertical planes diagonal to the sides, so as to form a diagonal face at the corner, which may be ornamented in conformity with the sides of the case, or independently, as is described, and this I claim.

My new design consists, in the second place, in combining with the diagonal face formed on the corner of the case, an ornamental console or tablet, such as is shown in the drawing, and this I claim.

My new design consists, in the third place, in forming the console or ornamental tablet in the manner shown in the drawing, and this I claim.

Executed this 20th day of September, A. D. 1869.

GEO. H. DAVIS.
